(57) **CLAIM**

The ornamental design for a foot scanner, as shown and described.

DESCRIPTION

FIG. 1 is a perspective view of the foot scanner according to our new design;

FIG. 2 is a left side view thereof;

FIG. 3 is a back side view thereof;

FIG. 4 is a front side view thereof;

FIG. 5 is a top view thereof; and,

FIG. 6 is a bottom view thereof.

Portions of the claimed design have been broken away and not shown for ease of illustration.

The right side of the foot scanner is a mirror image of the left side shown in FIG. 2.
